UNITED STATES PATENT OFFICE

ROBERT LARSEN, OF LOS ANGELES, CALIFORNIA

MACHINE FOR APPLYING DECORATIVE MATERIAL

Application filed April 14, 1930. Serial No. 443,960.

This invention relates to application of decorative materials to objects, and has particular reference to machines for applying decorative icings to cakes or other baked products upon which it is desired to reproduce a selected design.

Many products now offered upon the market are given a pleasing appearance by means of designs placed thereon in the form of decorations built up by application of a plastic material to the object in accordance with a predetermined design. For example, the plastic materials, such as a thick paint, wax, plaster or similar materials, have been placed upon the objects to produce the effect of a raised or embossed configuration thereon, the object decorated being rendered more pleasing to the eye than similar objects upon which a decoration of a flat design is used.

It has been the practice in the confectionery art to apply sugar icings to baked products, such as cakes, in which the icing, while still plastic is applied in accordance with a predetermined design to produce various pleasing configurations, and particularly icings of various colors have been used to further enhance the beauty of the finished cake. All of these decorative effects have heretofore been dependent upon the skill of the person applying the design, making the finished product costly and rendering it substantially impossible to accurately reproduce several articles of the same design.

It is an object of my invention therefore to provide a device for automatically reproducing designs in plastic material from a record or pattern so that the same design may be reproduced as many times as desired.

Another object of my invention is to provide a device for reproducing predetermined designs in plastic material in which the material may be applied in varied configurations of the same material.

Another object of my invention is to provide a device for reproducing designs in plastic material in which the design may be reproduced in various types, kinds or colors of materials.

Another object of my invention is to provide a device for reproducing designs in plas-

tic material from a record or pattern in which the different parts of the design may be reproduced in lines of varying configuration and in varying kinds or colors of materials.

Another object of my invention is to provide a device for reproducing designs in plastic material from a record or pattern in which the different parts of the design may be reproduced in lines of varying configuration and in varying kinds or colors of material. 55

Another object of my invention is to provide a device for reproducing designs in plastic material from a record or pattern in which the configuration of the design is controlled by the pattern and in which the selection of the configuration of the lines, as well as the selection of the kinds or colors of materials, will be accomplished automatically in accordance with the pattern. 60

Another object of my invention is to provide a device for reproducing designs in plastic material in which the plastic material will be applied in lines, the size of which is automatically controlled by controlling the rate of flow of the material to the object to be decorated in accordance with the record or pattern. 70

Other objects and purposes of my invention will be apparent from a study of the following description with reference to the accompanying drawings, wherein 80

Figure 1 is a diagrammatic view of a machine built in accordance with my invention and utilized for the purpose of decorating cakes; 85

Figure 2 is a detail view in side elevation of the feed pipe rack illustrated in Figure 1;

Figure 3 is a detail view, partly in section, of the feed rack illustrated in Figure 2; 90

Figure 4 is a detail sectional view of a valve to be utilized for controlling the rate of flow of the decorative material;

Figure 5 is a detail view, partly in section, of a clutch which may be used to connect an object supporting turntable for rotation thereof; 95

Figure 6 is a detail view showing the arrangement of the controlling magnets for the decorating arm illustrated in Figure 1; 100

Figure 7 is a detail view showing the arrangement of a retracting spring utilized to control the movements of the decorating arm shown in Figure 1;

5 Figure 8 is a detail plan view of the connecting attachment between the decorating arm and the decorating nozzles through which the plastic material is supplied;

10 Figure 9 is a detail view in side elevation, showing the connecting attachment illustrated in Figure 8;

Figure 10 is a plan view, partly in section, of the record or pattern and the controlling resistors for the magnets shown in Figures 1

15 and 6;

Figure 11 is a side elevation, partly in section, of the pattern or record device illustrated in Figure 10, and

20 Figure 12 is a diagrammatic view showing the wiring system which may be utilized in practicing my invention.

Referring to the drawings, I have illustrated an embodiment of my invention which may be utilized in applying decorative icing 25 to cakes or to other baked products in which the object to be decorated may be placed upon a turntable 10, preferably rotatably mounted upon a base 11. Immediately above the turntable 10 I have illustrated a decorating arm 30 12 supported upon a plurality of links or levers 13 and 14. The link or lever 13 is pivotally mounted upon a shaft 15 and has a rearwardly extending portion 16 thereof extending beyond the pivot for operative engagement to the armature 17 of a solenoid 18 by means of a link 19.

It will be observed that the link or lever 13 connects to the decorating arm 12 at a point intermediate the ends of this arm, while 40 one end of arm 12 is pivotally connected as at 21 to the link or lever 14. The opposite end of the link or lever 14 is pivotally connected to a short link 22 which in turn is also rotatably mounted upon the same shaft 15 45 which supports the link 13. From an inspection of Figure 1, it will be observed that the length of the link 13 between the shaft 15 and the decorating arm 12 is exactly the same as the length of the lever 14 between the pivotal connection 21 and the link 22. Also, it 50 will be observed that the short link 22 is of the same length as the distance between the pivotal connection 21 on the arm 12 and the point of attachment of the link 13 to the arm 12. This construction, therefore, constitutes a parallelogram support for the decorating arm 12.

A solenoid 23 having an armature 24 is 60 connected by means of a link 25 to the lever 14, preferably at the point of connection of the link 22 to the link 14. It will also be observed that the direction of movement of the armature 24 under the influence of 65 the solenoid 23 is at substantially right angles

to the movement of armature 17 under the influence of its solenoid 18.

A biasing spring 26 secured between the lever 13 and the decorating arm 12 normally biases the decorating arm 12 in a direction opposite to that in which the arm 12 and the link 13 will be relatively moved under the influence of solenoid 23. The arm 12 is provided, at the end thereof opposite to the point of attachment of the link 14, with a substantially U-shaped clip or connecting attachment 27 which may be attached to tubes or nozzles through which the decorative material is to be applied to the object to be decorated.

70 The construction thus far described constitutes a supporting mechanism for the decorating arm 12 and the nozzle carrying attachment 27 in which the position of the nozzle carrying attachment with reference to the turntable 10 may be controlled through the varying energization of the solenoids 18 and 23, the effect of solenoid 18 being to cause the attachment 27 to describe an arc, the radius of which is the length of the lever 13, while the effect of solenoid 23 will be to move the attachment 27 through another arc which is substantially at right angles to the arc determined by lever 13. In this manner varying the relative energization of the two solenoids 18 and 23 will cause attachment 27 to move in any direction in a plane parallel to the surface of the turntable 10.

75 The path which is to be described by the attachment 27 may be determined by means of a record or pattern 28 (see Figure 10), which I have illustrated as comprising a base strip of flexible non-conductive material 29, for example, a strip of canvas upon which may be secured a plurality of strips 30, 31, 32 and 33 of conducting material. The base strip 29 may be suitably wound upon a spool 34, which is journaled in the side walls 35 of a control box 36. A winding spool 37 also journaled in the control box 36 and driven through the agency of a pulley 38 and a shaft 39 may be used to draw the pattern 29 from the spool 34 and through the control box 36.

80 Mounted in the control box 36 I have illustrated a pair of resistance tubes 40 and 41, one above and one below the path described by the pattern 29 in its movements from spool 34 to spool 37. Each of the resistance tubes 40 and 41 has wound thereon a pair of resistors, those upon tube 40 bearing the reference characters 42 and 43, while those upon tube 41 bearing the reference characters 44 and 45. The resistors are preferably formed of some non-insulated resistance wire and are wound in such manner as to present the surfaces of the wire for engagement with the conducting strips 30-33 as the pattern passes from one of the spools to the other. If desired, a pair of deflecting rollers 46 and 47 may be provided between the resistance

120

125

130

tubes 40 and 41 to insure electrical contact between the resistors and their respective conducting strips on the pattern 29.

From an inspection of Figures 10 and 11 it will be observed that, as the pattern 29 passes from spool 34 to spool 37, the contact strip 30 will engage different turns of resistance wire of the resistor 45 in accordance with the convolutions of the conducting strip 30. In the same manner, the resistor 44 will have different turns thereof engaged by the conducting strip 31 in accordance with the configuration of this strip. In like manner resistors 42 and 43 will be similarly engaged by conducting strips 32 and 33, respectively. By properly securing the various conducting strips to the canvas base with the relative positions of the convolutions thereof arranged in accordance with a predetermined design, the amount of effective resistance of the resistors 42-45 may be varied in accordance with the predetermined selected plan.

Referring to Figure 12, it will be observed that resistor 42 is connected in circuit with solenoid 18, while resistor 44 is connected in circuit with solenoid 23, the opposite terminals of the solenoids 18 and 23 being connected to a suitable source of electric energy represented as a battery 48. The deflecting rollers 46 and 47 may be utilized, if desired, as means for connecting the opposite terminal of the battery 48 to the conducting strips 30-33, by making these rollers of conducting material and connecting the same to one terminal of the battery 48.

As the various convolutions of conducting strips 32 and 31 engage different turns of the resistors 42 and 44, respectively, varying amounts of current will be supplied respectively to the solenoids 18 and 23.

Referring again to Figure 1, I have illustrated a plurality of sources of plastic decorative material represented as containers 49, 50, 51 and 52. These containers may be filled with different kinds of material, for example, container 49 may be filled with an icing of a particular color, for example, white while containers 50, 51 and 52 may, respectively, contain other colored icings, such as, pink, green, brown, etc. From the lower portion of the container 49 a feed pipe 53 extends to a junction 54 from which a plurality of branch feed pipes 55, 56 and 57 may lead. The tubes 55, 56 and 57 are preferably made of some flexible material, to one end of which is secured a rigid tube section 58 secured to a hollow hub 59, which is in turn supported upon a hollow shaft 60. From the opposite side of the hub 59 a second rigid section 61 of the tube may extend, to the opposite end of which is secured a further flexible tube 62 which terminates in a nozzle or funnel 63. The hollow shaft 60 is provided with an opening 64 therethrough for registration with a similar opening 65 in a solid valve

plunger 66, the assembled structure constituting a valve for controlling the flow of the material through the tubes 55, 58, 61 and 62. The hollow hub 59 is provided with a pair of internally extending bosses 67 so positioned with reference to the openings 64 that when the tube sections 58-61 are moved from the vertical position, the bosses pass out of alignment with the opening 64, this construction constituting an automatic cut-off valve for preventing passage of material to the nozzle 63 during the time that the tubes 58 and 61 are vertical.

The remaining branches 56 and 57 of the feed pipe 54 are similarly provided with rigid sections and valve devices, as was described with reference to the branch 55.

From the container 50, a feed pipe 68 extends to a plurality of branches 69, 70 and 71 which are also provided with rigid sections 85 and valve structure similar to those described with reference to 55. In like manner, container 51 is connected by means of a feed pipe 72 to a plurality of branches 73, 74 and 75, while container 52 is connected by means 90 of a feed pipe 76 to a plurality of branches 77, 78 and 79.

The valve structures for all of the branches 55-79 of the feed pipes from the different sources of plastic material may be conveniently assembled upon a supporting structure 80 by mounting all of the hubs 59 upon the hollow shaft 60, which may be formed as a continuous sleeve secured to upright supports 81 and 82, constituting a part of the supporting frame 80, there being an opening 64 in the sleeve 60 for each of the hubs mounted thereon. The valve 66 may likewise be constituted as a continuous rod extending throughout the length of the hollow sleeve 60,

with openings therein for alignment with each of the openings 64 for each of the hubs mounted thereon. The valve 66 may be suitably controlled by connecting the same to the armature 83 of a solenoid 84, mounted upon a bracket 85 attached to one of the uprights 81 of the frame 80, so that energization of the solenoid 84 will cause the valve 66 to move with respect to the sleeve 60 and thus control the size of the opening through which the plastic material may be supplied to the nozzles. The valve 66 may be suitably biased to a closed position by means of a spring 86 opposing the effect of solenoid 84. In the application of the decorative material, it may be desired to have the lines described by the material of varying sizes, and this may be controlled by suitably controlling the valve opening as by connecting the solenoid 84 to the resistor 43. Such connection allows the rate of flow of the material to be controlled in accordance with the position of conducting strip 33 on the pattern 29.

Referring again to Figures 2 and 3, it will be observed that each of the branches of the

feed pipes 54, 68, 72, and 76 terminates in a suitable funnel or nozzle. These funnels or nozzles have openings therein of different configuration and are preferably of the character well known in the confectionery art, where they have been used for the purpose of applying decorative icings to cakes, candies, etc. Preferably, the three nozzles associated with the three branches of each of the feed pipes shall have a different configuration with respect to each other, while the first nozzle of each group of the branches shall be similar, the second nozzle of each group shall be similar, and likewise, the third nozzle of each group shall be similar. I have designated the nozzles associated with each of the branches with suitable reference characters, that designated by the reference character 63 being associated with branch 55, nozzle 87 associated with branch 56, 88 with branch 57, 89 with branch 69, 90 with branch 50, 91 with branch 71, 92 with branch 73, 93 with branch 74, 94 with branch 75, 95 with branch 77, 96 with branch 78, and 97 with branch 79. Each of the nozzles 63, 87, etc. is arranged to be normally positioned in suitable openings 98 in a rack 99 secured to the frame 80, with the flexible tube 62 leading thereto of such length as to allow the rigid sections of the branches of the feed pipes to assume a normal vertical position, with the valves comprised by the hubs 59 and sleeves 60 in a normally closed position. The vertical positioning of the rigid sections of the feed pipe branches is insured by mounting a weight 100 on the lowermost end of the rigid sections of each of the branch feed pipes so that the rigid sections are always biased to their vertical position. In order to insure the flow of plastic material from the containers 49—52, it is advisable to apply pressure to the material within the containers. For this purpose I have illustrated a pump 101 for maintaining a supply of air under pressure within a tank 102, whence the pressure is applied as by means of a conduit 103 to the upper portion of each of the containers 49—52. The pump 101 may be driven in any suitable manner as usual by a motor 104, and may be controlled in any well known manner to maintain the pressure at the desired value. The motor 104 may also be utilized to drive the pattern or record 28 by connecting the motor to the drive pulley 38, as by means of a belt 105. While the attaching arm may be moved over the surface of the turntable in any desired direction, under the influence of solenoids 18 and 23, it may be desirable to rotate the object placed upon the turntable 10, and to accomplish this I have illustrated the turntable 10 as connected by means of a gearing 106 to a shaft 107, which shaft may be connected in driving relation with a driving shaft 108 by means of a suitable clutch 109

controlled by means of a magnet 110. The driving shaft 108 may be driven in any suitable manner, though I have illustrated the same as connected to be driven by the motor 104, as by means of a belt 111. 70

The rotational movement of the turntable 10 may, if desired, be suitably controlled by means of the pattern 28 by connecting the magnet 110 to a contact brush 112 secured to one of the side walls 35 of the control box 36, and extending across the pattern 29 to such position as to engage a contact strip 113 mounted upon the pattern 29 at a suitable point thereon as to pass between the ends of the adjacent resistors 42, 43 and 44, 45, respectively. 75

The operation of the device thus far described for applying a decorative design to a cake may be outlined as follows:

Assuming that the containers 49, 50, 51 and 52 have been supplied with suitable frosting or icing material in a plastic form and that pressure has been supplied thereto from the pump 101 and tank 102, the material from each of the containers will be passed into the feed pipes leading therefrom and to the several branches leading from each of the feed pipes. However, since all of the rigid sections of each of the feed pipes are in their vertical positions, with the respective hubs thereof aligned with the valve openings 64, the material can pass only to the valve structure comprising hubs 59, sleeves 60 and valve 66. 90

The object to be decorated, such as a cake 114, may be placed upon the turntable 10 and the pattern or record of the particular design may be placed in the control box 36. Current may now be supplied from the battery or other source of supply 48 to start the motor 104, and thereby cause the pattern 28 to be unwound from spool 34 and wound up on spool 37. As the pattern or record 28 passes from one of the spools to the other, the conducting strips 31 and 32 will pass over their respective resistors 44 and 42 to variably energize solenoids 18 and 23. The initial configuration of the conducting strips 31 and 32 should be such as to cause the connecting attachment 27 to be moved toward the rack 99 to select the particular one of the nozzles 63, 86, etc. which it is desired to be used for the first portion of the decoration or design desired. This operation will be understood as comprising the effect of substantially slight energization of the solenoid 18 so that the arm 12 will be moved under the influence of spring 20 toward the rack 99, while a simultaneously slight energization of the solenoid 23 will cause the arm 12 to assume whatever position is necessary to select the particular nozzle desired. 110

As the pattern 28 continues past the resistors 42—44, the selected nozzle will be moved toward the cake to such position as may be desired as the starting point for the decora- 120

tive design. As the nozzle (for example 63) is moved from the rack the consequent pull on tube 62 will cause the rigid section of the branch pipe leading to nozzle 63 to be tilted 5 from the vertical position, thus opening the passage between the hub 59 and the sleeve 60. However, no material will flow to the nozzle 62 at this time, until the conducting strip 33 engages its resistor 43. Engagement of the 10 strip 33 and resistor 43 will cause current to flow from the battery or source of current 48 to the magnet 84 controlling the valve 66, thus causing valve 66 to align its opening 65 with the opening 64 in the sleeve 60. Material 15 from container 49 may now pass to the nozzle or funnel 63 and thence to the cake or other object to be decorated.

Further movement of the pattern or record 20 causing the convolutions of the conducting strips 31 and 32 to successively touch various turns of resistance wires on the resistors 44 and 42 will cause the arm 12 to so move as to make the connecting attachment 27 and the nozzle 63 carried thereby describe a path of 25 predetermined configuration in accordance with the predetermined design for which pattern 28 is a record.

For example, the movements of the attachment 27 and nozzle 63 may be such as to produce a wavy line of icing material upon the 30 cake, or there may be inscribed upon the cake a written word or in fact, any predetermined design which may be desired.

The quantity of material which is to be 35 utilized in forming the design may be varied to vary the width or depth of the material applied by means of convolutions of the conducting strip 33 in their passage over resistor section 43, energizing the valve magnet 84 to 40 a greater or less degree, in accordance with the predetermined plan.

As the pattern moves further through the control box it may be desired that another color of material shall be applied, in which 45 case the convolutions of conducting strips 31 and 32 should be such as to cause the arm 12 to move back toward the rack 99 to replace the nozzle 63 therein and to select another of the nozzles, such as nozzle 89, which is supplied with material from another of the containers 50. Restoring the nozzle 63 to the 50 rack 99 allows the weight 100 to again restore the rigid sections 58-61 of the branch feed pipe to its vertical position, thus cutting off 55 the supply of material to the nozzle 63. It will, of course, be assumed that prior to the movement of the arm and nozzle 63 from the cake, the magnet 84 is deenergized, allowing the spring 86 associated with the armature 83 60 of this magnet to return the valve 66 to the closed position, thus preventing material passing to the nozzle 63 during this movement. After restoring the nozzle 63 to the 65 rack 99, magnet 18 and 23 will be so controlled by the pattern as to withdraw the connecting

attachment 27 from nozzle 63 and to move the attachment into such position as will permit it to engage nozzle 89. Thereafter, further movement of the pattern 28 will cause the nozzle 89 to be moved to a desired position above the cake, and thence to describe the configuration desired in forming the decoration thereon. The further movement of the pattern also controls the energization of magnet 84 to allow material to pass to the nozzle 88 in such quantities as are desired and determined by the pattern 28.

Assuming that some other portion of the design desired is to be formed in lines of a configuration differing from those determined by the nozzle 63, another of the nozzles having the desired configuration on its tip may be selected, in a manner described with reference to the selection of nozzles 63 and 89. That is, assuming that a line of the same material as is fed through nozzle 63, but having a different configuration, is desired, the attachment 27 may be moved to such position as to select the proper nozzle, for example 87 (which being connected to the same feed pipe 53 leading from container 49, is supplied with material from this container), and this nozzle 87 may then be moved over the cake to describe the desired configuration.

The selection of the nozzles, the selection of colors and the design which will be described by the material flowing therethrough, may be controlled in accordance with the predetermined pattern.

The foregoing description, however, involves only the movement of the nozzles and the arm 12 in a plane parallel to the surface of the turntable 10. If it is desired that the design should be applied at varying heights upon the surface of the cake 114, or if it is desired that a design should be described upon the vertical sides of the cake 114, such vertical operations may be accomplished by mounting the links or levers 13 and 22 upon the shaft 15 in such manner as to permit the links to be moved upwardly and downwardly under the influence of magnet 115.

Referring to Figure 6, it will be observed that the shaft 15 comprises a rod, the lower end 116 of which is suitably squared and inserted in a supporting bearing 117, the opening through which is also squared to fit the squared end of the shaft. The upper end of the shaft 15 terminates in an armature 118 lying within the solenoid 115, so that energization of solenoid 115 causes a lift of the shaft 15 or the structure mounted thereon. Adjacent the square portion of the shaft 15 I have illustrated a collar 119 secured to the shaft usually as by means of a set screw 120.

Resting upon the collar 119 is a washer or sleeve 121, upon the upper end of which rests link 22. Immediately above link 22 the shaft 15 passes through an opening in link 13, while spring 20, secured to the link 13 and the

shaft 15, as at 122, holds the assembled link structure against vertical displacement relative to the collar 119. The assembled structure, therefore, constitutes a support for the links 13 and 14, which allows these links to be moved vertically as the shaft 15 is lifted vertically under the influence of magnet 115.

It will also be observed that the connection between the extending end 16 of link 13 with the link 19 and the armature 17 of solenoid 18 is accomplished by means of a vertically extending rod 123 which is secured to the end 16 of link 13 and is surrounded by the link 19, so that lifting of the entire link structure 13, 14, 16 may be accomplished without disconnecting the armature 17 of solenoid 18 from these links. In like manner, a rod 124 secured to the end of link 25 and extending vertically downward therefrom constitutes the pivotal engagement between link 25 and the armature 24 of solenoid 23, and insures that lifting of the link structure does not disconnect solenoid 23 from the link structure.

The magnet for solenoid 115 is connected in circuit with the battery or source of power 48 and with a resistor 45 so that the passage of conducting strip 30 in the pattern 28 will cause the solenoid to be energized with varying amounts of current to thereby vary the height to which the link structure will be lifted or allowed to be lowered under the influence of gravity.

With the structure for lifting and lowering the arm 12 described, decorations may be placed upon the cake which have dimensions in a vertical plane.

Assuming that it is desired to inscribe upon the cake to be decorated a line which may be formed by holding the nozzle stationary and rotating the turntable, a suitable conducting strip 113 placed upon the pattern 28 at the proper point, may be utilized to cause energization of the magnet 110 to connect the turntable for rotation by motor 104.

It may also be desired to describe certain portions of the decoration with peculiar formations, such as by rotating the nozzle 63, as is the usual practice in the production of what is known as the "rosebud" decoration frequently found upon cakes and similar confections. In order to provide for such operation with my device, I have illustrated the nozzle 63 as being rotatable with reference to the attaching clip 27 (see Figures 8 and 9), by constructing the nozzle 63 with a reduced portion 125 surrounded by a collar 126, which collar constitutes the point of engagement between the attachment clip 27 and the nozzle 63. The collar 126 may be maintained in fixed relation to the nozzle 63 as by means of a washer 127 and suitable lock nuts 128. The employment of the nozzle attachment described permits rotation of the nozzle 63 by the force of any device which will turn or twist the tube 62.

In order to provide for the rotary movement of the nozzle 63 I have illustrated the rigid section 61 of the branch feed pipe to which the tube 62 is attached as being rotatably secured to the boss 59. A small pinion 129 is rigidly secured to the rigid section 61 of the branch feed pipe in such position that when the rigid section 61 is tilted from the vertical position, the pinion will be brought into effective engagement with a gear rack 130 mounted upon the supporting structure 80 in front of the assembled bosses. The gear rack may be reciprocated in any suitable manner, such as by connecting the rack 130 to the armature of a solenoid 131, mounted upon a bracket 132, which in turn is secured to the supporting frame 80.

Energization of the solenoid 131 will cause the rack to move toward the left (see Figure 2) and will thus cause rotation of the flexible section 61 of the branch feed pipes which happens to be tilted from its vertical position, as occurs when this branch feed pipe is in active use. The control of solenoid 131 may also be automatic, as by providing upon the record or pattern 28 an additional contact strip 133 for engagement by means of contact brush 134 mounted within the control box 36 in a manner similar to that described with reference to brush 112. It will be noted that the conducting strip 133 is mounted upon the opposite side of the base canvas strip 29 to that upon which strip 113 is mounted, so that there will be no interference between these two strips. The brush 134 may be suitably connected in circuit with the source of power 48 and the solenoid 131, so that at whatever portion in the design it is desired to produce a rosebud or similar configuration, requiring the rotation of the nozzle, the engagement of the conducting strip 133 and the brush 134 will produce the desired rotational effect on the nozzle 63.

It will thus be observed that I have provided a machine which may be utilized to reproduce from a pattern a design for which the pattern may be made, and that this design may be reproduced as many times as is desired in an automatic manner, making it unnecessary to employ a skilled worker for the reproduction of the design.

While the employment of my invention shown and described herein appears to be the preferred form of my invention, I do not wish to be limited to any of the details herein, except as defined in the appended claims.

I claim:

1. In a device for applying decorative material to an object to be decorated, a plurality of sources of different decorative materials, a feed pipe and a nozzle for each source, an arm attachable to any of said nozzles, means for moving said arm in all directions in at least one plane, a pattern for determining the configuration of the finished decoration and

for determining the selection of the material to be applied in different parts of the decoration, and means connecting the pattern and said moving means to cause said arm to select nozzles and to describe the decoration in accordance with said pattern.

2. In a device for applying decorative material to an object to be decorated, a source of decorative material, a plurality of feed pipes connected to said source, each terminating in a nozzle of a configuration different from that of the others, an arm attachable to any of said nozzles, means for moving said arm in any direction in at least one plane, a pattern for determining the configuration of the finished decoration and for determining the selection of the different nozzles for different parts of the decoration, and means connecting said moving means and said pattern to cause the arm to select the nozzles and to describe the decoration in accordance with the pattern.

3. In a device for applying decorative material to an object to be decorated, a plurality of sources of different decorative material, a plurality of feed pipes connected to each source each of which terminates in a nozzle differing in configuration from the remainder, an arm attachable to any of said nozzles, means for moving said arm in any direction in at least one plane, a pattern for determining the configuration of the finished decoration and for determining the selection of the different nozzles for different parts of the decoration, and means connecting said moving means and said pattern to cause the arm to select the nozzles and to describe the decoration in accordance with the pattern.

4. In a device for applying decorative material to an object to be decorated, a source of decorative material, a feed pipe therefrom, having a nozzle through which the material flows to the object, means for applying pressure to said source of material, a valve in said feed pipe for controlling the flow of material therethrough, an arm for carrying the nozzle, a pattern for determining the configuration of the finished decoration, means connecting the pattern and said arm to cause the arm to move over the object in accordance with the pattern, and means operably responsive to movement of said nozzle by said arm for controlling said valve.

5. In a device for applying decorative material to an object to be decorated, a source of decorative material, a feed pipe therefrom, having a nozzle through which the material flows to the object, means for applying pressure to said source of material, a valve in said feed pipe for controlling the flow of material therethrough, an arm for carrying the nozzle, a pattern for determining the configuration of the finished decoration, means connecting the pattern and said arm to cause the arm to move over the object in accordance with the pattern, and means for con-

trolling said valve in accordance with said pattern.

6. In a device for applying decorative material to an object to be decorated, a source of decorative material, a feed pipe therefrom, having a nozzle through which the material flows to the object, means for applying pressure to said source of material, a valve in said feed pipe for controlling the flow of material therethrough, an auxiliary valve in said feed pipe for also controlling the flow of material, an arm for carrying the nozzle, a pattern for determining the configuration of the finished decoration, means connecting the pattern and said arm to cause the arm to move over the object in accordance with the pattern, means operably responsive to movement of said nozzle by said arm for controlling said valve, and means for controlling said auxiliary valve in accordance with said pattern.

7. In a device for applying decorative material to an object to be decorated, a source of decorative material, a feed pipe therefrom, having a nozzle through which the material flows to the object, means for applying pressure to said source of material, a valve in said feed pipe for controlling the flow of material therethrough, an arm for carrying the nozzle, a pattern for determining the configuration of the finished decoration, means connecting the pattern and said arm to cause the arm to move over the object in accordance with the pattern, and means operable by said pattern for controlling said valve to determine the rate of flow of said material in accordance with a predetermined design.

8. In a device for applying decorative material to an object to be decorated, a source of decorative material, a feed pipe therefrom, having a nozzle through which the material flows to the object, an arm for carrying the nozzle, a pattern for determining the configuration of the finished decoration, means connecting the pattern and said arm to cause the arm to move over the object in accordance with the pattern, and means for rotating said object while said object is receiving material from said nozzle.

9. In a device for applying decorative material to an object to be decorated, a plurality of sources of different decorative materials, a feed pipe and a nozzle for each source, said feed pipes each including a pivotally mounted section biased to a normal position, an arm for carrying said nozzle, a pattern for determining the configuration of the finished decoration, means connecting said arm and said pattern to cause the arm to move over the object in accordance with the pattern and to draw the section of the feed pipe from its normal position, a normally closed valve in said feed pipe for controlling the flow of material therethrough and operable to an

open position upon movement of the feed pipe section from its normal position.

10. In a device for applying decorative material to an object to be decorated, a source of decorative material, a feed pipe therefrom, having a nozzle through which the material flows to the object, an arm for carrying the nozzle, a pattern for determining the configuration of the finished decoration, a plurality of interconnected levers supporting said arm, electromagnetic means for moving said levers to move said arm horizontally in one direction, electromagnetic means for moving said arm horizontally in a direction at an angle to said first direction, the combined action of said electromagnetic means causing said arm to move in any direction over a flat surface dependent upon the degree of energization of said electromagnetic means, electromagnetic means for controlling the lifting and lowering of said arm, resistance means controlled by the pattern for controlling the degree of energization of said electromagnetic means to cause the arm to move in accordance with the pattern, and resistance means controlled by said pattern for variably controlling said lifting and lowering means in accordance with said pattern.

11. In a device for applying decorative material to an object to be decorated, a source of decorative material, a feed pipe therefrom, having a nozzle through which the material flows to the object, an arm for carrying the nozzle, a pattern for determining the configuration of the finished decoration, means connecting the pattern and said arm to cause the arm to move over the object in accordance with the pattern, means for rotating said nozzle with respect to said arm, and means under the control of said pattern for determining the point in the configuration of the finished decoration at which rotation of the nozzle is to occur.

12. In a device for applying decorative material to an object to be decorated, a source of decorative material, a feed pipe therefrom, having a flexible section to which is secured a nozzle through which the material flows to the object, an arm for carrying the nozzle, a pattern for determining the configuration of the finished decoration, means connecting the pattern and said arm to cause the arm to move over the object in accordance with the pattern, means rotatably mounting said nozzle on said arm, means for rotating said flexible section of said feed pipe, and means under the control of said pattern for operating the rotating means at that point in the configuration of the finished decoration at which rotation of the nozzle is desired.

13. In a device for applying decorative material to an object to be decorated, a source of decorative material, a nozzle connected to said source, an arm carrying said nozzle, a magnet for reciprocating said arm in a given

horizontal direction, a second magnet for reciprocating said arm in a horizontal direction substantially at right angles to said first direction, a circuit for each magnet, a pattern for determining the configuration of the decoration comprising a pair of circuit controls for individually controlling said magnets to move said arm in accordance with said pattern.

Signed at Los Angeles, California this 9th day of April, 1930.
